UNITED STATES PATENT OFFICE.

ROBERT H. GOLDSTEIN, OF LOS ANGELES, CALIFORNIA.

DESIGN FOR A TABLE ORNAMENT.

49,114.

Specification for Design.

Patented May 30, 1916.

Application filed December 11, 1915. Serial No. 66,395. Term of patent 7 years.

● To all whom it may concern:

Be it known that I, ROBERT H. GOLDSTEIN, a citizen of the United States, residing at Los Angeles, in the county of Los Angeles and State of California, have invented a new, original, and ornamental Design for a Table Ornament, of which the following is a specification, reference being had to the accompanying drawing, forming a part thereof.

The figure is a perspective view of a table ornament, showing my new design.

I claim:

The ornamental design for a table ornament, as shown.

R. GOLDSTEIN.

Witness:

ELWOOD H. BARKELEW.
